US00D338151S

United States Patent [19]

Paulin et al.

[11] Patent Number: Des. 338,151

[45] Date of Patent:  Aug. 10, 1993

[54] GARMENT HOOK

[75] Inventors: Pierre H. Paulin; Francois Kergoet, both of Paris; Michel Chalard, Villemomble, all of France

[73] Assignee: Jacob Delafon, Paris, France

[] Term: 14 Years

[21] Appl. No.: 5,860

[22] Filed: Mar. 15, 1993

Sheets 3 and 4 of drawings of a design patent application by McKeone, et al., admitted prior art.

Pp. 2-48 of undated Kohler ad, admitted prior art, showing inter alia K-8136 soap dish.

Pp. 2-79 of a Kohler ad dated Aug. 1991, admitted prior art, showing inter alia Model K-10501 soap dish.

An Aug. 1, 1969 Bradley ad showing inter alia Model 912 robe hook.

A Kohler ad and engineering drawings, admitted prior art, showing brackets for supporting fixtures.

An undated ad, admitted prior art, for Crescente fixtures.

Primary Examiner—Brian N. Vinson
Attorney, Agent, or Firm—Quarles & Brady

[57] CLAIM

The ornamental design for a garment hook, as shown and described.

DESCRIPTION

FIG. 1 is a perspective view taken from the top, front and right side of a garment hook showing our new design;

FIG. 2 is a top plan view thereof;

FIG. 3 is a front elevational view thereof;

FIG. 4 is a right side elevational view thereof, the left side being a mirror image of the right side shown;

FIG. 5 is a bottom plan view thereof; and,

FIG. 6 is a rear elevational view thereof.

The fragmentary broken line representation of mounting holes in FIG. 6 is for the purpose of illustration only and forms no part of the claimed design.
